UNITED STATES PATENT OFFICE.

FREDERICK J. WOOD AND PATRICK L. LACHAPELLE, OF HOQUIAM,
WASHINGTON.

SAWMILL SET-WORKS.

SPECIFICATION forming part of Letters Patent No. 650,626, dated May 29, 1900.

Application filed February 5, 1900. Serial No. 4,061. (No model.)

To all whom it may concern:

Be it known that we, FREDERICK J. WOOD and PATRICK L. LACHAPELLE, citizens of the United States, residing at Hoquiam, in the county of Chehalis and State of Washington, have invented new and useful Sawmill Set-Works, of which the following is a specification.

Our invention is an improved power apparatus for the set-works of a sawmill-carriage, the object of our invention being to provide a simple and efficient combination of devices for applying power to the set-works to adjust the knees on the head-block and set the saw-log.

Our invention consists in the combination, with a pair of oppositely-disposed friction-wheels on the set-shaft of the carriage, of a traveling power-cable and a laterally-movable power-shaft rotated by said cable and having a friction-wheel disposed between the opposing faces of the wheels on the set-shaft, and hence adapted to be engaged with either of said wheels and to be disengaged from both of them.

Our invention further consists in the peculiar construction and combination of devices hereinafter fully set forth, and particularly pointed out in the claims.

In the accompanying drawings, Figure 1 is a top plan view of a sawmill-carriage provided with our improved power apparatus for the set-works thereof. Fig. 2 is a longitudinal sectional view of the same. Fig. 3 is a vertical transverse sectional view taken on the line 3 3 of Fig. 1. Fig. 4 is a detail sectional view taken on the line 2 2 of Fig. 1. Fig. 5 is a detail sectional view taken on the line 5 5 of Fig. 4. Fig. 6 is a detail sectional view at right angles to Fig. 4.

The sawmill-carriage 1 travels on the track 2 and is provided with the hollow head-blocks 3, the knees 4, supported by and guided in said hollow head-blocks, and the screw-shafts 5, disposed and having their bearings in the hollow head-blocks and having the flange-collars 6, which receive the screw-threads on the screw-shafts, and hence travel back and forth thereon when said screw-shafts are rotated, said flange-collars being disposed in recesses 7 in the under sides of the knees,

and hence communicating their motion to the said knees, and being thereby adapted to move the latter back and forth on the head-blocks, as will be readily understood.

55

A longitudinally-disposed set-shaft 8 is journaled in suitable bearings 9 on the carriage, near the inner side thereof, and said set-shaft is connected to the screw-shafts 5 by the pairs of miter gear-wheels 10, which are keyed to 60 said set-shaft and said screw-shafts, and hence rotate the said screw-shafts in unison with each other when said set-shaft is rotated.

A pair of friction-wheels 11 are disposed on the set-shaft 8 at suitable points thereon and 65 at a suitable distance apart and are keyed to said set-shaft. The opposing friction-faces 12 of the said wheels are of truncated conical form, as shown in Fig. 1.

A shaft 13, which is disposed at right angles to the set-shaft 8 at a point between the friction-wheels 11, is mounted at one end in a pivoted bearing-box 14, the pivotal bolt 15 of which extends through the beam 16, that constitutes a portion of the frame of the carriage. The said shaft 13 has its bearing at a suitable distance from its inner end in an eccentric sleeve 17, which is supported and adapted to rotate in a suitable bearing 18, which is bolted on a plate 19, that is bolted 80 on the platform of the carriage, as at 20. A shifting lever 21 is secured firmly to one end of the said eccentric sleeve, or the same may be formed integrally therewith, as shown in Fig. 5. A friction-cone 22 is keyed to the 85 shaft 13 at its inner end and is disposed between the opposing truncated conical faces of the friction-wheels 11, the latter being at such a distance apart that by shifting the shaft 13 to a position exactly midway between said 90 friction-wheels the said friction-cone will be out of engagement with both of them, as shown in Fig. 1. By turning the hand-lever in one direction or the other, and thereby partially rotating the eccentric sleeve, the shaft 95 13 may be moved in either direction, and hence cause the friction-cone to be brought in operative contact with either of the friction-wheels. A lock-plate 23 is supported by a pair of standards 24, which rise from the 100 bearings 18, and the lever 21 bears against said lock-plate and is provided with a key-

bolt 25, which is adapted to engage a notch 26 in the upper side of the lock-plate when the hand-lever is in a vertical position and lock the shaft 13 in its normal position, with 5 its friction-cone out of engagement, with both of the friction-wheels. A sheave 27 is keyed on the shaft 13 at a suitable point between the bearings of the said shaft.

An endless traveling cable 28 is arranged 10 parallel with the track and below the same and is supported by a single sheave 29 and a double sheave 30, the cable passing twice around the double sheave to form a bight 31, which is engaged by a tension - sheave 32, 15 mounted in suitable bearings and capable of movement back and forth in or upon a suitable supporting - guide 33. A weight 34 is connected to the movable bearing of the tension-sheave by a suitable cord or chain 35, the 20 function of the said weight and of the tension-sheave being to take up slack in the endless cable and preserve the latter at suitable operative tension. The upper side of the cable passes over the sheave 27 on the shaft 13 25 and under the pair of guide-sheaves 36, which have suitable bearings supported by the carriage, the said guide-sheaves being arranged on opposite sides of the sheave 27. The endless cable when the sawmill is at work is 30 driven by any suitable source of power and travels continuously in one direction, and hence causes the shaft 13 to be in constant rotation, regardless of whether the sawmill-carriage is moving or stationary on its track. 35 The operation of our invention is as follows: When it is desired to set or move the knees on the head-blocks in either direction, the friction-cone is brought in contact with the appropriate friction-wheel by moving the lever 21 so as to shift the inner end of the shaft 40 13, this being done by an operator stationed on the sawmill-carriage. The shaft 13, carrying the friction-cone, being constantly rotated by the endless traveling cable, as soon 45 as the friction-cone is brought into contact with one of the friction-wheels the set-shaft 8 will be rotated and the latter will communicate rotary motion to the screw-shaft to which it is geared, and hence cause the knees 50 to move simultaneously and at a uniform rate

of speed. By means of the hand-lever 21 and the eccentric sleeve the pressure of the friction-cone against the friction - wheel with which it is engaged may be regulated according to the distance the knees are to be moved 55 and the speed with which it may be requisite to move them, and hence by our improved power-applying apparatus the knees may be moved and adjusted rapidly and with great nicety either to move the knees inward on the 60 carriage when a sawlog is to be mounted thereon or to set them so as to determine the thickness of the lumber to be sawed from the sawlog.

Having thus described our invention, we 65 claim—

1. In sawmill set-works, the combination, with a pair of oppositely-disposed friction-wheels on the set-shaft of the carriage, of a traveling cable, and a laterally - movable 70 power-shaft, rotated by said cable, and having a friction-wheel disposed between the opposing faces of the wheels on the set-shaft, and adapted to be engaged with either of said friction-wheels, and to be disengaged from 75 both of them, for the purpose set forth, substantially as described.

2. The combination, with a traveling sawmill-carriage, of an endless traveling cable, a set-shaft mounted on the carriage, having a 80 pair of friction-wheels, a power-shaft mounted on the carriage, and having the sheave engaged and rotated by the endless cable, a friction-wheel on said power-shaft, disposed between the friction-wheels on the set-shaft, 85 and a lever to operate said friction-wheel, substantially as described.

In testimony that we claim the foregoing as our own we have hereto affixed our signatures in the presence of witnesses.
